DUAL SEAT FOR A PASSENGER VEHICLE

Alan R. Cripe, Richmond, Va., assignor to United Aircraft Corporation, East Hartford, Conn., a corporation of Delaware

Filed May 29, 1967, Ser. No. 7,296

Term of patent 14 years

(Cl. D15—8)

FIG. 1

FIG. 2

FIGURE 1 is a front view of the dual seat; and FIGURE 2 is a side view of the dual seat. The essential features of the design reside in those portions shown in full lines on the drawing.

I claim:

The ornamental design for a dual seat for a passenger vehicle, substantially as shown and described.
